UNITED STATES PATENT OFFICE

127,004

DESIGN FOR AN INCINERATOR

John W. Hebert, Bay City, Mich.

Application June 3, 1940, Serial No. 92,790

Term of patent 7 years

To all whom it may concern:

Be it known that I, John W. Hebert, a citizen of the United States, residing at Bay City, in the county of Bay and State of Michigan, have invented a new, original, and ornamental Design for Incinerators, of which the following is a specification, reference being had to the accompanying drawing, forming a part thereof.

Fig. 1 is an isometric view of an incinerator showing my new design.

Fig. 2 is a top plan view thereof.

The opposite side of the incinerator is exactly the same as the side shown in the drawing.

I claim:

The ornamental design for an incinerator, as shown and desired.

JOHN W. HEBERT.
